UNITED STATES PATENT OFFICE.

ARTHUR RAYNSFORD, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 4, 1921. Serial No. 466,827.

To all whom it may concern:

Be it known that I, ARTHUR RAYNSFORD, a citizen of the United States, residing at New York, in the county of Bronx, State of New York, have invented certain new and useful Improvements in Telephone-Exchange Systems, of which the following is a full, clear, concise, and exact description.

This invention relates to a telephone exchange system wherein automatic and manual offices are interconnected by trunks which may be selected by subscribers of the automatic office from certain levels of the selectors when a connection is desired with a subscriber in a manual office. The trunks terminate at the manual office before operators who complete the connections.

The object of the invention is to provide a circuit arrangement which will take care of all the necessary operations in calls of this character with interoffice trunks having only two conductors.

Referring to the drawing, which shows only so much of a telephone exchange system as is necessary for a comprehension of the invention, the invention will more readily be understood from a detailed description of the operation.

Upon the removal of the receiver by the calling party at substation A associated with the automatic office his line is automatically extended in the well-known manner by line finder 1 to a first selector 2. The subscriber now operates his dial 3 to set the first selector opposite a group of trunks terminating in the desired manual office whereupon the selector automatically seizes one of these trunks. The relay 4 now operates over the calling line circuit and operates a slow relay 5 which in attracting its outer left armature applies tone from source 6 to the calling line to notify the calling subscriber that his line has been extended to a trunk leading to the manual office. Relay 5 at its middle left armature applies ground potential to the test multiple 7 of the seized trunk which ground potential will be maintained after the calling subscriber restores his receiver and releases selector 2 as will be explained in detail and will be removed only when the operator at the manual office disconnects from the other end of the trunk, thus, insuring that this trunk will not be selected unless it is idle.

The apparatus to the left of the dotted line

is located in the automatic office and the apparatus to the right is located at the manual office. The attraction of the right armature of relay 4 closes a loop including the trunk conductors in series to operate a relay 10 at the manual office for lighting a calling lamp 16 thereby indicating the arrival of the call at the operator's position. This circuit is as follows:

Free pole of battery, normal contact of relay 8, resistance 9, relay 10, lower normal contact of relay 29, lower trunk conductor, conductor 11, right contact of relay 4, relay 12, right winding of polarized relay 18, resistance 14, upper trunk conductor, upper normal contact of relay 29, and marginal relay 15 to ground. Relays 12 and 15 are marginal and do not operate in this circuit, but relay 10 operates and lights the calling lamp 16. The operator in response to the lighting of this lamp inserts the answering plug into the answering jack which operates relay 17 over an obvious circuit. Answering supervisory lamp 24 also lights. Relay 17 operates relay 18. Relay 18 in attracting its right armature extinguishes the calling lamp 16 and in attracting its inner left armature short-circuits the resistance 9, which reduces the resistance of the above traced circuit and results in the operation of the marginal relays 12 and 15. Relay 12, operates slow releasing relay 19 which in attracting its outer left armature disconnects the tone source from the calling line and in attracting its inner left armature closes a circuit for relay 5 to hold the same energized independently of the condition of relay 4. Relay 15, at the manual office, in operating closes a bridge, including a retardation coil 20, across the trunk beyond the condensers 21 and 22 thereby completing a circuit for and operating the answering supervisory relay 23 to extinguish the answering lamp 24 by means of a shunt circuit. The operator now presses her listening key 25, ascertains the desired number and completes the connection in the well-known manner. Upon the response of the subscriber at substation B in the manual office, relay 26 operates and extinguishes the calling supervisory lamp 27 in the usual manner.

The subscribers may now converse, talking battery being supplied to the substation B from the cord circuit in the manual office

and to substation A through the windings of relay 4 in the automatic office. The operator may now actuate key 28 to operate relay 29 to reverse the direction of the current flow in the loop leading back to the automatic office including the polarized relay 13. Relay 29 locks itself to ground at the right normal contact of relay 18. Relay 13 operates and in attracting its armature 10 operates relay 30 to reverse the direction of current flow in the calling line to operate the message register or coin collector (not shown).

Upon the replacement of the receiver by the party at substation A, relay 4 releases. In retracting its right armature, this relay removes the short circuit from the high resistance relay 31, which is now included in the loop circuit, releasing marginal relay 15 15 at the manual office, which in retracting its armature opens the bridge across the trunk including the retardation coil 20. The answering supervisory relay 23 releases causing the lighting of lamp 24 to notify the operator that the subscriber at substation A 20 has replaced his receiver. The replacement of the receiver by the party at substation A releases the finder 1 and selector 2 in the well-known manner, but since relay 31 is 25 operated, relay 19 is held operated which in turn holds relay 5 operated. Relay 5 at its middle left armature holds ground on the test multiple 7 to prevent it from being seized before the operator has removed the 30 plug. When the plug is removed from the trunk jack relay 31 releases, releasing relay 19 which in turn releases relay 5 to remove the busy condition from multiple 7. The removal of the plug also deenergizes relay 35 40 13 which in releasing releases relay 30 to restore the normal connections of the battery to the trunk. The removal of the plug also releases relay 17 which in turn releases relay 18. Relay 18 in retracting its right 45 armature unlocks relay 29, which restores the normal connections of the battery to the trunk at the manual office. Relay 18 in releasing its outer left armature releases relay 8 which restores the normal connection of 50 resistance 9 to the battery and in retracting its inner left armature removes the shunt from around said resistance. The function of the slow releasing relay 8 is to prevent the accidental locking of relays 10, 31, 12, 13 55 and 15 in the loop circuit when the operator withdraws the plug. Due to relay 8 being slow to release it maintains battery disconnected from relay 10 until after relay 31 has released long enough to deenergize relay 19 which in retracting its right armature opens the loop.

Inasmuch as relay 5 is locked under control of relay 19 which is in turn controlled by the operator, the calling party can flash 60 the lamp 24 while the plug is in the trunk

jack without releasing the connection, and thus secure the attention of the operator if he should so desire.

What is claimed is:

1. In a telephone system, the combination 70 with automatic and manual offices, of telephone lines terminating therein, trunks each consisting of two conductors only for interconnecting said offices, automatic switches controlled by the calling subscriber 75 for selecting one of said trunks, means for automatically connecting a tone source at the automatic office to the calling line upon the selection of said trunk, a lamp at the manual office, means for lighting said lamp 80 upon the selection of said trunk and means actuated by the operator in response to the call for disconnecting said source and extinguishing said lamp.

2. In a telephone system, the combination 85 with automatic and manual offices, of telephone lines terminating therein, trunks each consisting of two conductors only for interconnecting said offices, automatic switches controlled by the calling subscriber 90 for selecting one of said trunks, a lamp associated with said trunk at the manual office lighted by the selection of said trunk, a link circuit adapted to be connected to said trunk by the operator and having a supervisory 95 relay therein, a bridge across said trunk, a trunk relay operated by the connection of said link circuit to said trunk, a circuit including said bridge closed by said trunk relay for operating said supervisory relay, a 100 lamp in said link circuit extinguished by the operation of said supervisory relay, and means controlled by the calling subscriber 105 in replacing his receiver for releasing said trunk relay to deenergize said supervisory relay to light said lamp.

3. In a telephone system, the combination with automatic and manual offices of telephone lines terminating therein, a trunk 110 consisting of two conductors only for interconnecting the same, a loop circuit including said trunk conductors in series, a relay in said circuit at the manual office, a pair of condensers in said trunk at the manual office, a bridge across the trunk beyond said condensers, a link circuit having a supervisory 115 relay adapted to be connected to the trunk by the operator in responding to the call, means actuated by the connection of said link circuit to said trunk for reducing the resistance of said loop to operate said marginal relay to close said bridge to operate said supervisory relay, and a relay at the automatic office in circuit with the calling line for controlling said loop circuit.

4. In a telephone system, the combination with automatic and manual offices, of telephone lines terminating therein, trunks each consisting of two conductors only for interconnecting said offices, automatic switches 120 for selecting one of said trunks, means for automatically connecting a tone source at the automatic office to the calling line upon the selection of said trunk, a lamp at the manual office, means for lighting said lamp 125 upon the selection of said trunk and means actuated by the operator in response to the call for disconnecting said source and extinguishing said lamp.

controlled by the calling subscriber for selecting one of said trunks, means for automatically connecting a tone source at the automatic office to the calling line upon the 5 selection of said trunk, a lamp at the manual office lighted upon the selection of said trunk, a marginal relay at the automatic office, and an energizing circuit therefor including said trunk conductors in series 10 closed by the operator in responding to the call for disconnecting said tone source.

5. In a telephone system, in combination with automatic and manual offices, telephone lines terminating therein, trunks each consisting of two conductors only for interconnecting said offices, automatic switches controlled by the calling subscriber for selecting one of said trunks, means for applying a tone at the automatic office to the calling 20 line upon the selection of the trunk, a loop circuit including said trunk conductors, a marginal relay at the automatic office and a marginal relay at the manual office, a bridge across the trunk at the manual office controlled by said latter relay, a supervisory relay, a lamp controlled thereby, a circuit for said relay including said bridge, and means actuated by the operator in responding to the call for reducing the resistance of said 30 loop circuit to operate said marginal relays to disconnect said tone source and extinguish said lamp.

6. In a telephone exchange system, the combination with automatic and manual 35 offices, of telephone lines terminating therein, trunks each consisting of two conductors only interconnecting said offices, automatic switches controlled by the subscribers at the automatic office for selecting one of said 40 trunks, a loop circuit including said trunk conductors in series, two relays including said loop circuit in the manual office, one of which is marginal and the other non-marginal said non-marginal relay being operated 45 upon the seizure of the trunk, a calling lamp lighted thereby, a pair of condensers in said trunk beyond said marginal relay, a bridge across the trunk beyond said condensers, a link circuit adapted to be connected to the 50 trunk by the operator in responding to the call, means actuated thereby for reducing the resistance of said loop circuit to operate said marginal relay to close said bridge, a supervisory relay in said link circuit controlled by said bridge, and a relay at the 55 automatic office in series with the calling line for controlling said loop circuit.

7. In a telephone system, the combination with automatic and manual offices, of telephone lines terminating therein, trunks each consisting of two conductors only interconnecting said offices, automatic switches controlled by the calling subscriber for selecting one of said trunks, means for automatically 60 connecting a tone source at the auto-

matic office to the calling line upon the selection of said trunk, a loop circuit including said trunk conductors, a marginal relay at the automatic office controlling said tone source, and a marginal relay at the 70 manual office, means for closing said circuit upon the seizure of said trunk, a link circuit adapted to be connected to said trunk and having a supervisory relay therein, means for controlling said supervisory relay by said last named marginal relay, means actuated by the connection of said link circuit to said trunk for reducing the resistance of said loop to operate said marginal relay, and a relay at the automatic 75 office in series with the calling line for controlling said loop circuit.

8. In a telephone system, in combination with automatic and manual offices, telephone lines terminating therein, trunks each consisting of two conductors only for interconnecting said offices, automatic switches controlled by the calling subscriber for selecting one of said trunks, a relay in said trunk operated upon the seizure thereof for placing a busy condition on the seized trunk, a loop circuit including the trunk conductors in series, and a relay therein at the automatic office for independently holding said busy relay operated, the continuity of said 90 loop circuit being controlled solely from the manual office.

9. In a telephone system, a pair of offices, a telephone line, a circuit for connection therewith, a trunk having two conductors only interconnecting said offices, a relay operated upon the extension of said line to said trunk at the originating office for connecting said circuit to said line, a link circuit adapted to be connected to the trunk at the distant office, a circuit including said link, a marginal relay controlling the same, a marginal relay in said trunk at the distant office, a loop circuit including said 105 trunk and marginal relays for energizing the same closed upon the connection of said link circuit to said trunk, means actuated by one of said marginal relays for disconnecting said first mentioned circuit from said line and means actuated by the other for closing the circuit including said link, a supervisory relay in said link circuit and means for operating the same upon the closure of said circuit.

10. In a telephone system, a pair of offices, a telephone line, a circuit for connection therewith, a trunk having two conductors only interconnecting said offices, a relay operated upon the extension of said line to one end of said trunk for connecting said circuit to said line, a link circuit adapted to be connected to the trunk at the other end, a circuit including said link, a marginal relay controlling the same, a marginal relay at the other end of said trunk, a loop 115 120 125 130

circuit including said trunk and marginal relays for energizing the same closed upon the connection of said link circuit to said trunk, one of said marginal relays disconnecting said first mentioned circuit from said line and the other closing the circuit including said link, a supervisory relay in said link circuit operated by the closure of said circuit, a line relay in said telephone line controlling said loop circuit, a high re-

sistance relay, and a short circuit about the same closed by said line relay and opened by the release thereof to include said high resistance relay in said loop circuit to release said marginal relay at the other end of said trunk to open the circuit including said link to release said supervisory relay.

In witness whereof, I hereunto subscribe my name this 2nd day of May, A. D. 1921.

ARTHUR RAYNSFORD
